DESIGN FOR A BRIDGE FOR AN OPHTHALMIC MOUNTING

Theodore R. Uhlemann, Antioch, Ill.

Application March 11, 1940, Serial No. 90,816

Term of patent 3½ years

To all whom it may concern:

Be it known that I, Theodore R. Uhlemann, a citizen of the United States, residing at Antioch, in the county of Lake and State of Illinois, have invented a new, original, and ornamental Design for a Bridge for an Ophthalmic Mounting, of which the following is a specification, reference being had to the accompanying drawing, forming a part thereof, in which

Figure 1 is a perspective view showing the

bridge in full lines and showing the straps, and guards in dotted lines;

Fig. 2 is a plan view of the mounting showing the bridge in full lines and showing the straps, and guards in dotted lines; and

Fig. 3 is a section on the line 3—3 of Fig. 2.

I claim:

The ornamental design for a bridge for an ophthalmic mounting, substantially as shown.

THEODORE R. UHLEMANN.
